Wilson & Clark ATTORNEYS

UNITED STATES PATENT OFFICE.

LEO E. EVSLIN, OF NEW YORK, N. Y., ASSIGNOR, BY MESNE ASSIGNMENTS, TO DORA STALBERG, OF PHILADELPHIA, PENNSYLVANIA.

ARTIFICIAL TOOTH.

1,292,952.

Specification of Letters Patent. Patented Jan. 28, 1919.

Application filed December 28, 1911. Serial No. 668,234.

To all whom it may concern:

Be it known that I, LEO E. EVSLIN, residing at New York, in the county and State of New York, have invented certain new and 5 useful Improvements in Artificial Teeth, of which the following is a specification.

This invention relates to improvements in artificial teeth, and more particularly to artificial teeth of that class comprising a porcelain facing and a backing which may be 10 detachably secured together.

One of the objects of the invention is to produce a tooth of this character wherein the backing is disposed over the cutting edge of 15 the porcelain to relieve the latter of biting strains, the parts being of such structure that the facing may be properly fitted to the backing before the parts are finally secured together, and so that the facing may be 20 replaced by another facing interchangeable with it when occasion arises.

Another object of the invention is to provide a porcelain facing having a groove of a particular kind therein for the reception of 25 a correspondingly shaped pin to which the backing may be first temporarily secured, the arrangement of parts being such that when the backing is temporarily secured to the pin, with the protecting tip of the backing 30 extended over the incisive edge of the facing, with the pin engaged in the groove of the facing as in the final relation of parts, the pin with the attached backing may be readily removed from the facing and assembled 35 therewith again without disturbing the fit of the backing relatively to the facing and particularly the fit of the protecting tip of the backing to the incisive edge of the facing.

40 Another object is to provide a facing and appropriate pin of such construction and relation that a backing may be adapted to the facing which will afford great strength to the assembled structure and maximum retention between backing and facing.

Other objects and aims of the invention more or less broad than those stated above will be in part obvious and in part specifically referred to in the course of the following description of the elements, combinations, arrangements of parts, and applications of principles constituting the invention; and the scope of protection contemplated will appear from the appended 55 claims.

In the accompanying drawings, which are to be taken as a part of this specification, and in which I have shown merely illustrative forms of embodiment of the invention;

Figure 1 is a section of a facing which 60 may be employed in connection with my invention;

Fig. 2 is a view of a pin adapted to be used in connection with the facing shown in Fig. 1, showing also in section a backing 65 adapted to be connected with said pin;

Fig. 3 is a view of a facing such as shown in Fig. 1 in connection with a pin and backing such as shown in Fig. 2, the backing being shown connected to the pin, and the pin 70 just entering the groove of the facing;

Fig. 4 is a view similar to Fig. 3, but showing the pin about half way in the groove of the facing;

Fig. 5 is a view similar to Fig. 4, showing 75 the pin in position in the groove and the backing in its proper relation to the beveled incisive edge of the facing;

Fig. 6 is a detailed perspective of a pin such as may be used in connection with my 80 invention;

Fig. 7 is a detail perspective of a boxing such as may define a groove in the facing of a tooth embodying my invention;

Fig. 8 illustrates how my invention may 85 be applied in connection with molar teeth;

Figure 9 illustrates a modified form of the invention shown in Figs. 1 to 8.

Referring to the numerals on the drawings, and particularly to Figs. 1 to 9, inclusive, 1 indicates a facing for a tooth embodying my invention, the form of tooth illustrated being a bicuspid. As shown, the opposite ends of the tooth are preferably beveled, the upper or cervical edge as at 90 2, and the lower or biting edge, as at 3. There is a pin socket or groove 4 opening into the back of the facing 1, and preferably defined by a boxing shown in Fig. 7 baked 95 into the material of the facing during the manufacture of the latter. Preferably, for purposes hereinafter explained, the inner wall 5 of the groove is, at least throughout a part of its length, curved on the arc of a circle, and preferably also said groove 100 terminates adjacent the biting edge of the facing in the socket 7, which is tapered as shown. 8 indicates a pin, preferably having milled sides, and having a face 9, 105 curved to correspond with the curve of the 110

inner wall of the groove in the facing, and having preferably a tapered end 10 to correspond with the end of the socket in the facing. The pin is also provided with 5 an attaching portion 11, which is adapted to extend through an aperture 12 in the backing 14. In practice the pin is slipped into the groove of the facing, and the backing prepared with the aperture 12 is engaged 10 over the attaching portion of the pin, and then the backing is swaged into shape over the facing, so that the backing will have portions 15 and 16 engaging the bevels of the cervical and incisive edges 15 of the facing respectively. The backing is now temporarily secured in its desired fixed relation to the pin by means of wax or the like, and it will be apparent that the pin may be withdrawn from the facing, carrying the backing with it, and brought back to place again as often as may be desirable or necessary in the course 20 of the manipulations attending the particular operation, the portion of the backing 25 which engages over the bevel of the biting edge going readily to place, as indicated from Figs. 3, 4 and 5, so that the backing needs to be shaped to the facing but once, and that at the beginning of 30 the mechanical operation. This result follows from the fact that the inner wall of the groove in the facing and the surface of the pin that slides on said wall are curved on the arc of a circle. 35 It will be evident that many of the details of this invention may be varied and are not of the greatest importance. For instance, I have shown the groove in the facing defined by the boxing shown in Fig. 40 7, as of a dove tailed cross section. Obviously it might just as well have a circular or other similar undercut cross section or a cruci-form or T cross section or the like, so long as the surfaces of the groove and 45 of the pin which determine the direction of movement of the pin within the groove are upon the arc of a circle. Obviously too, in the case of such change in the cross section of the groove the shape of the pin 50 would change accordingly. It will also be evident that the invention is not limited to any particular form of tooth, though a bicuspid is shown for convenience. For instance, in Fig. 8 I show how the invention 55 may be used in connection with a molar tooth; this structure shows a completed dummy for bridge work ready to be united with its abutments; it shows the metallic structure besides the backing, viz: metal 60 articulating surface and lingual wall of the tooth.

Referring to the modification shown in Fig. 9, the structure is like that already described, except that the posterior surface 65 of the facing is on a curve, substantially

as shown, extending from the cervical to the biting edge. The pin and the groove are as in the figures already described.

It is particularly desirable that the facing shown in this figure have its posterior 70 surface, extending longitudinally from some point, as 17, to the incisive edge 18, curved on an arc parallel to the arc of the pin groove. With such an arrangement, the mere fitting of the facing with 75 a backing provides at the same time a self-protecting tip, without the necessity for grinding in order to produce the same. In this form of construction also the manipulation of the parts is facilitated, while 80 the assembled structure possesses great strength.

As many changes could be made in this construction without departing from the scope of the following claims, it is intended 85 that all matter contained in the above description or shown in the accompanying drawing shall be interpreted as illustrative only and not in a limiting sense.

Having thus described my invention, what 90 I claim as new and desire to secure by Letters Patent is:

1. An artificial tooth member having a guide portion formed longitudinally along its inner surface, and said guide being 95 curved longitudinally of its length, a backing for said tooth member, and means connected with said backing having a curved surface adapted to slide along said curved guide whereby to direct said backing to a 100 predetermined position upon said tooth member.

2. An artificial tooth member having a guide formed longitudinally along its inner surface, said guide being of substantially 105 uniform cross section throughout its length, and being curved longitudinally in a path convex to the rear surface of said tooth member, a backing for said tooth member, means connected with said backing adapted 110 to slide along said groove in a curved line defined by said groove to direct said backing to a predetermined position upon said tooth member, and said means and said guide having coöperative formations for 115 preventing lateral displacement of said means from said guide during any relative longitudinal movement between them.

3. An artificial tooth member having a guide portion formed longitudinally along 120 its inner surface, and said guide being of substantially uniform cross section throughout its length and being curved convex to the rear surface of said tooth member longitudinally and uniformly in the arc of a 125 circle continuously throughout its length, said tooth member being formed with a socket-like portion adjacent the incisive edge thereof into which one end of said curved guide terminates, a backing for said tooth 130

member, and means connected with said backing curved longitudinally to correspond to the curvature of said guide so as to be slidable along with said guide and having 5 a portion adapted to engage within said socket.

4. An artificial tooth comprising a facing provided with a groove extending along its inner surface, the bottom wall of said groove, 10 being curved longitudinally in the arc of a circle, a pin slidable in said groove having a surface curved on the arc of a circle engaging the curved wall of said groove to be guided in a curved path thereby, a backing 15 carried by said pin for engaging the inner surface of said facing, said facing being beveled off at one end, and said backing having a portion for engaging the bevel of said facing.
- 20 5. An artificial tooth comprising a facing provided with a groove extending vertically along its inner surface, said groove opening at one end through one of the end surfaces of the facing, the bottom walls of 25 said groove being curved on the arc of a circle, a pin slidable in said groove having a curved surface engaging the curved wall of the groove to be guided thereby, and a backing carried by said pin.
- 30 6. An artificial tooth comprising a facing provided with a groove extending along its inner surface, the bottom wall of said groove being curved longitudinally in the arc of a circle, the side walls of said groove 35 being undercut to provide relative shoulder portions longitudinally of the groove, a pin slidable in said groove having a surface curved on the arc of a circle engaging the curved bottom wall of the groove to be 40 guided in a curved path thereby, said pin also having shoulder portions to engage the shoulder portions of the groove to retain the curved surface of the pin in engagement with the curved wall of the groove, and a 45 backing carried by said pin.
7. An artificial tooth comprising a fac-

ing provided with a groove extending along its inner surface, the bottom wall of said groove being curved longitudinally, in the arc of a circle, a pin slidable in said groove 50 having a surface curved on the arc of a circle engaging the curved wall of said groove to be guided in a curved path thereby, and the inner surface of said facing adjacent one end thereof being disposed in 55 a plane substantially parallel to the plane of the bottom wall of the adjacent end of said groove, for the purpose set forth.

8. A tooth having an approximately vertical and flat lingual surface and a gingival 60 margin or surface sloping from the lingual surface to the labial surface of the tooth; also said tooth provided with a curved recess or cavity which opens out of the lingual surface and the gingival margin. 65

9. A tooth having a curved recess or cavity which opens out of the lingual surface and gingival margin, the upper wall of the recess or cavity extending in the direction of the incisal edge; a backing for said tooth; 70 and a curved pin for uniting the tooth to the backing, said pin adapted to have a slidable relation in the recess or cavity, entering the recess or cavity at the gingival margin of the tooth. 75

10. A tooth or facing having a curved recess or cavity opening out of the lingual surface and also its gingival margin; said recess or cavity being wedge shaped in cross section; a wedge shaped pin curved throughout its length conforming to and adapted to enter and fit the recess or cavity in said tooth or facing, said pin having a head; and backing for the tooth provided with an opening to receive the head of the pin. 80 85

In testimony whereof I affix my signature in the presence of two witnesses.
